UNITED STATES PATENT OFFICE.

DAVID P. CLEVELAND, OF OAKLAND, CALIFORNIA, ASSIGNOR TO UNIVERSAL PAINT REMOVER AND MOTOR CLEANING COMPANY, OF DALLAS, TEXAS, A COMMON-LAW COMPANY.

PROCESS OF REMOVING SURFACE FINISH.

Application filed September 5, 1924. Serial No. 736,042.

To all whom it may concern:

Be it known that I, DAVID P. CLEVELAND, a citizen of the United States of America, residing at Oakland, in the county of Alameda and State of California, have invented 5 certain new and useful Improvements in Processes of Removing Surface Finish, of which the following is a specification.

This invention relates to new and useful 10 improvements in processes of removing surface finish.

The invention has particularly to do with the direction upon a surface of a hot fluid containing caustic alkali or equivalent ingredients. 15

The invention has particularly to do with the direction upon a surface of a hot fluid containing caustic alkali or equivalent ingredients. Heretofore such fluids have been 20 blown or ejected onto the surface under pressure, such as steam and air.

In my Patent No. 1,355,074, Oct. 5th, 1920, the process described involves the applying of a caustic alkali solution by means 25 of a pressure, such as steam. The solution is atomized or ejected by means of a pressure. I have found that under certain weather conditions a cloud or mist is present at the work, in such a form as to obscure the work. I have also discovered, by 30 experiment and research, that the alkaline liquor may be applied at a temperature below the boiling point of water and free from steam or air pressure, with very satisfactory results; also at a less cost than is possible with my aforesaid patented process.

The principal object of the invention is to deliver the alkaline solution to the surface in a simple and inexpensive manner 40 and to overcome certain objections present in other processes. Where the solution is put on the surface by steam or where steam is sprayed onto the surface at the same time, a cloud or bank of vapor obscures the work from the view of the workman particularly during cold weather. Where air is used it must be compressed and heated and conveyed to the work while hot. A further object of the invention is to flow a 45 hot alkaline solution onto the surface, whereby the finish is softened or disintegrated, so that it may be later removed by means of a brush or other means.

Another object is to apply a hot caustic 50 alkaline solution at a substantially constant

temperature and a substantially constant fixed strength.

In carrying out the invention I elevate a tank containing the alkaline solution, heat said solution and utilize gravity in flowing 60 it onto the surface for the finish to be removed. The solution upon reaching the surface may have a temperature ranging from 150 degrees Fahrenheit to 200 degrees, Fahrenheit. After the alkaline solution has 65 been delivered to the surface, a jet of steam may be sprayed upon the same to clean it, or hot water or air may be employed; the process being finished up with a stream of cold or unheated water. The use of steam 70 may be entirely eliminated by flowing the hot alkaline solution onto the surface to soften or disintegrate the finish, and then removing the finish by means of a brush or other means, and finally washing off the 75 surface with water.

In order to carry out the process, some apparatus is necessary and in the accompanying drawings such an apparatus is 80 shown as an example.

Fig. 1 is an elevation of an apparatus designed to carry out the invention.

Fig. 2 is a cross section taken on the line 2-2 of Fig. 1, and

Fig. 3 is a front elevation of a rack upon 85 which vehicles may be driven for treatment.

In the drawings the numeral 10 designates a suitable tank having a filling pipe 11 in its top, said pipe including a cut-off 90 valve 11'. This tank must be placed at a suitable elevation above the work to obtain a gravity flow. I have shown the tank mounted in a bracket 12 supported on a column 13, but it may be supported in any 95 suitable manner, as on an upper floor in the building where the work is being done.

The alkaline liquid placed in the tank must be heated and I do not wish to be limited to the means, manner or method 100 of so heating, or to the degree of temperature to which it is heated. I have found it practical and satisfactory to mount a coil 14 in the tank with its upper end protruding through the top of said tank and 105 its lower end projecting through the side of the tank near the bottom of the latter. Steam is supplied to the coil by a pipe 15 which is connected with an elbow 15' so that the coil may be disconnected and the 110

tank removed when desired. Most any form of receptacle, suitable for the purpose may be used and any desirable heating medium may be employed for heating the liquid in 5 the receptacle.

The lower end of the coil extends through 10 the side of the tank near the bottom. A valve 14' is connected in the extension of the coil outside of the tank. A hose 16 is connected with the coil and has a nozzle 17 on its lower end by which steam or hot water may be directed upon the work, but the nozzle may be omitted. A discharge pipe 18 leads from the tank under the coil 15 extension and includes a controlling valve 18'. A hose has its upper end connected with the pipe 18 and is provided with a nozzle 20 at its lower end. For supplying air, water or other fluid a pipe 21 is supported 20 by the column 13 and includes a controlling valve 21'. A hose 22 leads from the pipe and has a nozzle 23 on its end.

For the purpose of illustration I have shown a rack 24 on which an automobile 25 may be supported, but it is to be understood that the invention is neither to be limited to the apparatus shown or the removing of finish coating from any particular object.

The essential feature of the invention is 30 the application of a hot finish removing liquid by a gravity flow and the elimination of steam or other fluid under pressure as an agent in applying said liquid. In order that the best results may be had it is necessary to heat the liquid to a temperature ranging from 150 to 200 degrees Fahrenheit. However the process is not to be limited to the degree of temperature, as this permits of considerable variation. A satisfactory solution consists of ten pounds of 35 caustic soda to each twenty-five gallons of water, but this may vary according to the work.

In removing finish coatings the hot alkaline solution is admitted to the hose 19 by 40 opening the valve 18' and permitting said liquid to flow from the nozzle 20 onto the surface. The finish coating will be disintegrated and will flow in a solvent state 45 from the article being treated. The surface may be washed with steam or hot water from the coil by opening the valve 14 and directing the nozzle 17 toward the work. Water or air may be obtained from the hose 50 55 22 and nozzle 23.

If desired the heated solution may be applied to the surface, sufficiently hot to soften or disintegrate the finish, which may be removed by means of a stiff brush, and 60 the surface finally washed off.

This method is simple and inexpensive as it obviates the necessity of using pressure to put the finish removing liquid on the surface and does away with the use of steam

if desired as the coil may be connected with 65 a return to the boiler. The finish removing liquid is flowed onto the surface by gravity and is never impelled or sprayed by steam or air pressure. While steam may be used by directing it on the work to remove the 70 softened or disintegrated finish, said steam is applied separately and not as a spray or conductor for the removing fluid. Also the steam may be supplied from any source and need not come from the coil 14, which 75 would be omitted if the tank was otherwise heated. The solution is maintained at substantially a constant temperature, but is subject to variation. The liquid is also kept at a substantially fixed strength for each 80 operation.

This application is a continuation, in 85 part of my application Serial No. 544,364, filed March 16, 1922.

What I claim, is:

1. A process of removing finish coating 90 consisting in heating an alkaline solution to a temperature above 150 degrees Fahrenheit and below the boiling point of water, and then flowing said solution without artificial pressure onto the surface to be treated in a solid continuous stream of restricted cross area.

2. A process of removing finish coating, 95 which consists in heating an alkaline solution in an elevated tank to a temperature above 150 degrees Fahrenheit and below the boiling point of water, then flowing said solution in a solid continuous stream of restricted cross area by gravity onto the 100 surface being treated, said solution being applied free from steam or artificial pressure, and then utilizing the heating agent for cleansing the surface treated.

3. A process of removing finish coating, 105 which comprises the steps of flowing in a solid continuous stream of restricted cross area by gravity upon the surface being treated, a hot alkaline solution maintained at a temperature less than the boiling point 110 of water and at a substantially constant strength during the entire flowing operation, then removing the disintegrated finish by the application of steam, and then washing the surface with water.

4. A process of removing finish coating from an article, which consists in heating an alkaline solution in an elevated tank to a temperature above 150 degrees Fahrenheit and below the boiling point of water, and then flowing said solution in a solid continuous stream of restricted cross area by gravity onto the surface being treated, said solution being applied free from steam or artificial pressure.

In testimony whereof I affix my signature.

DAVID P. CLEVELAND.
